UNITED STATES PATENT OFFICE.

JOHN G. BAKER, OF PHILADELPHIA, PENNSYLVANIA, ASSIGNOR TO THE
ENTERPRISE MANUFACTURING COMPANY, OF SAME PLACE.

MACHINE FOR CUTTING MEAT.

SPECIFICATION forming part of Letters Patent No. 339,834, dated April 13, 1886.

Application filed November 2, 1885. Serial No. 181,646. (No model.)

To all whom it may concern:

Be it known that I, JOHN G. BAKER, a citizen of the United States, residing in Philadelphia, Pennsylvania, have invented certain 5 Improvements in Machines for Cutting Meat, of which the following is a specification.

My invention consists of certain improvements in the construction of the machine for cutting up plastic or yielding substances for 10 which Letters Patent No. 271,398 were granted, January 30, 1883, to the Enterprise Manufacturing Company, of Pennsylvania, as my assignees. Certain improvements on said machine which are illustrated in this application 15 form the subject of an application for Letters Patent filed by me December 15, 1884, Serial No. 150,375.

In the accompanying drawings, Figure 1 is 20 a vertical section of a cutting-machine embodying my present improvements, and Fig. 2 is a perspective view of several of the parts.

E is the outer shell or casing of the machine, corrugated longitudinally, as described in my said patent, and provided with the usual 25 hopper, K. The inner end of the casing is secured to and closed by a plate, m, which, by preference, forms part of the stand Y, to support the entire machine. This stand is shown as constructed for being clamped or otherwise 30 secured to a table, for the machine illustrated is designed to mince or cut up meat, and is intended for family or store-keepers' use. The outer end of the casing E is closed by a perforated plate, A, which is adapted to a seat in 35 the end of the casing, and is held in place by a screw-ring, B, the perforated plate being prevented from turning by a pin, i, on the casing, adapted to a recess, j, in the perforated plate. As described in my said application, 40 Serial No. 150,375, the retaining-ring B is provided with recesses and projections, to facilitate the screwing and unscrewing of the ring. The forcing or feed screw W, which is adapted to the interior of the casing E, has at its inner 45 end a journal, n, adapted to a bearing in the plate m, and is provided at its outer end with the usual handle, F. The shouldered end of the screw W, adjacent to the journal n, is provided with an annular recess for the reception 50 of anti-friction-bearing metal n'.

To a square or many-sided projection, p, at the opposite end of the feed-screw is adapted the knife D, which I have shown in the present instance as provided with four blades bearing against the inner face of the perforated 55 end plate, to produce a cutting action in connection therewith.

In constructing my previous machines, in the larger sizes I have found that, owing to the varying side pressure of the material on the feed-screw, the latter will in time cut or wear away the interior of the casing E, so that the outer end of the screw and the knife will, when the handle is turned, describe a planetary motion, and consequently it becomes difficult, if 60 not impossible, to keep the cutting edges of the knife up against the perforated plate A. To overcome this difficulty I form on the outer end of the feed-screw W a journal, d, and in the plate A a bearing, x, for this journal d. 65 This necessitates the passage of the journal d through the center of the knife; but I still retain in the outer side of the knife the convex recess w, with its side openings, for the purpose described in my aforesaid application for 70 patent.

The bearing may be formed in one piece with the plate A, or may be a separate piece, as illustrated in the drawings, secured to the plate in any convenient manner.

I make the bearing in the form of a projection for the twofold reason that a longer bearing is thus provided, and at the same time a handle is afforded for the manipulation and removal of the plate when desired, as described 75 in my aforesaid application.

I claim as my invention—

The combination of the casing and the feed-screw, having a knife and carrying at its outer end a journal, d, with a perforated end plate, 80 A, against which the knife cuts, the said perforated plate having a bearing, x, for the said journal, substantially as set forth.

In testimony whereof I have signed my name to this specification in the presence of two sub- 85 scribing witnesses.

JOHN G. BAKER.
